UNITED STATES PATENT OFFICE.

ARTHUR R. SIEGLER, OF DENVER, COLORADO.

REACTION TURBINE.

Application filed May 31, 1924. Serial No. 716,921.

To all whom it may concern:

Be it known that I, ARTHUR R. SIEGLER, a citizen of the United States, residing at Denver, in the city and county of Denver and State of Colorado, have invented certain new and useful Improvements in Reaction Turbines; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to improvements in turbines.

The problem to be solved in the design and construction of an efficient turbine, is to abstract all of the energy from the water or the liquid employed as the source of energy. This is usually attained when the liquid leaves the turbine with a zero velocity relative to the earth. Various types of turbines have been designed, some suitable for large volumes of water at low heads and others for small quantities of water at high heads, the latter type being what is usually referred to as impulse wheels.

It is well understood that impact or sudden retardation of the flow of the water causes a loss of energy, from which results a diminution of the absolute and relative velocities of flow. It is, therefore, desirable that the direction of the flow shall be changed gradually through an angle of 360 degrees.

It is the object of this invention to produce a turbine that shall be so constructed and designed that the flow of liquid, from which it derives its power, will be gradually reversed in direction without impact or sudden shock, and which will permit the water to leave with an absolute velocity which is substantially zero.

My improved turbine, briefly described, comprises a wheel mounted for rotation and provided with curved channels or passageways through which the liquid may flow and which are so designed that the absolute path of the water will be a straight line for a portion of its length and will thereafter be a gradual curve. Such a construction produces efficient operation.

My invention can be most clearly de-

scribed and will be most readily understood when reference is had to the accompanying drawing, in which the same is illustrated, and in which:

Fig. 1 is a plan view of my improved turbine, parts thereof being broken away to more clearly show the construction, the broken portions being a section taken on line 1—1, Fig. 3;

Fig. 2 is a section taken on line 2—2, Fig. 1;

Fig. 3 is a section taken on line 3—3, Fig. 1;

Fig. 4 is a diagram showing the absolute path of the water; and

Fig. 5 is a view showing three of the channels as though they were formed from sheet metal and laid in assembled relation.

My improved turbine consists of a circular disk-like member 1 provided with a central axle 2, a number of passageways or channels 3. The walls 4 of these channels correspond to the vanes of an ordinary turbine. It is upon the particular shape of these passageways or channels that my improved efficiency depends. As I have already pointed out, it is my object to so construct the passageways that the absolute path of the water will be substantially a straight line from the point *x* where it first enters the passage to the point marked *y* (Fig. 4) and thence in a gradual curve to point *z*. To accomplish this result, it becomes necessary to so curve the passageways that the resultant of the motion of the turbine and the movement of the water in the passage will be along line *x y* (Fig. 4). The point *y* (Fig. 4) corresponds to the point marked 5 in Fig. 1. When a certain particle of water has reached this point, it can no longer continue in the direction *x y*, but starts on its travel towards the exit 6. When the curvature of the passageway from point 5 to 6 is properly designed, the absolute path of a water particle from 5 to 6 will be substantially as shown in Fig. 4 and represented by the part *y z*.

As shown in Fig. 1 the channels from the periphery to the elbow or turn 5 have a gradual curve which may be determined by graphic methods, and which will produce an absolute path, which is substantially a straight line *x y*. The vanes, when properly designed, are concave on their forward sides and convex on the rear sides, in the manner shown in Fig. 1 when the direction of rota-

tion is clockwise. In order that the channels shall have the proper shape and be sufficiently numerous, they will have to overlap to some extent. Considering now Fig. 1, let us designate three adjacent channels as A, B and C. Channel A has a gradual curvature up to the point *a* or 5 where it makes an abrupt turn and proceeds radially inwardly to the exit openings 6. The channel B is identical in size and shape with channel A and has its point *b* extending over channel A. Channel C has its angle *c* extending over channel B and it also overlaps the channel A to some extent. This overlapping makes it necessary that the channels shall be twisted in the manner shown in Fig. 5 so as to prevent them having to be built up into three layers.

The passageways or channels are preferably first formed from thin sheet steel which can be twisted into the proper shape. The formed channels are then assembled in the manner indicated in Fig. 5, after which they are embedded in metal by having the latter poured over them in molten form. The passageways or channels may, of course, be formed in the casting by cores, which are

first assembled in a manner analogous to that shown in Fig. 5.

It is desirable that the cross section of the 30 passageways or channels shall be of constant area throughout their length.

Having now described my invention, what I claim as new is:

1. A turbine having a plurality of channels extending inwardly from the periphery towards the center, said channels having their outer ends curved in the direction of travel, and their inner ends substantially radial, said channels having portions inclined and overlapping adjacent channels. 35 40

2. A turbine having a plurality of channels extending inwardly from the periphery thereof towards the center, the channels being separated by vanes whose outer ends are 45 concave in the direction of travel and whose inner ends are substantially radial, the radial portions being joined to the outer curved portion at an angle, said angular portion of each channel overlapping the adjacent channel. 50

In testimony whereof I affix my signature.

ARTHUR R. SIEGLER.
